CABLE CONNECTOR

Henry D. Stecher, Lakewood, Ohio

Application July 22, 1947, Serial No. 762,549

12 Claims. (Cl. 285—6:5)

1
This invention relates to cable connectors and more particularly to improvements therein for the enhancement of adaptability and facility of use, efficiency and satisfaction of operation and economy of use and manufacture thereof.

It is among the objects of my invention to provide an improved cable connector having a wide range of adaptability and utility both in respect to the sizes of cables that may be securely received and gripped thereby and in respect to the certainty and facility with which the connector may in turn be secured to the wall, plate or junction box with which it is to be used. Another object of my invention is to provide a cable connector wherein cables, of a wide range of sizes, can, and inherently will be, held concentric of the connector when and as the same is gripped and secured thereto wherewith, inter alia, the conductors of the cable will be centrally disposed with relation to the axis of the connector and safely and uniformly spaced with respect to the surfaces thereof. Another object of my invention is to provide a connector that gives a positive electrical ground connection between the sheath of the cable and the wall of the outlet and junction box with which the connector is associated. Another object of my invention is to provide automatically adjusted seat or bottom support for the end of the sheath of the cable which support shall serve with equal utility and efficiency throughout the whole range of sizes of the cables adapted to be received and gripped in the connector. Another object is to provide a cable connector that is economical to manufacture and of sturdy and rugged construction and that is simple in design, foolproof, dependable and efficient in operation and inherently capable of a long and useful life under arduous conditions of service.

These and other objects and advantages will appear from the following description of a preferred form of my invention, reference being had to the accompanying drawings in which Figure 1 is a top plan view of my connector mounted on the wall of an outlet or junction box; Figure 2 is a side elevation of my connector showing the box wall in section; Figure 3 is a longitudinal section of my connector taken in the plane of the line 3—3 of Figure 1; Figure 4 is another longitudinal section taken along the planes of the broken line 4—4 of Figure 1; Figure 5 is a transverse section taken in the plane of the line 5—5 of Figure 2; Figure 6 is a longitudinal section of my connector in the planes corresponding to Figure 4 taken with the cable disposed therein and

the connector contracted and gripping the cable in operative relation, the cable, conductors and outlet box being shown fragmentarily; Figure 7 is a transverse section taken in the plane of the line 7—7 of Figure 6; and Figure 8 shows one of the clamping members of my connector in its flat sheet form prior to being curved and shaped for attachment to and incorporation in my connector.

10 In the preferred form of my invention herein illustrated my connector C comprises an externally threaded nipple 1 adapted to pass through and closely fit the aperture 2 in the wall 3 of the outlet or junction box, upon which nipple a nut 15 4 is threadedly carried to forcibly engage the inner or lower face of the wall 3, drawing the nipple downwardly as viewed to its snug lowermost position as shown; its movement through the aperture 2 being limited by the abutting engagement of the lower edges 5 and 6, and/or lugs 5a and 6a, of the cable clamping members 7 and 8 respectively with the upper and outer face of the wall 3 adjacent the aperture 2; the lowermost parts 9 and 10 of the said clamping members 7 and 8 being respectively welded, brazed or otherwise secured to the upper outer exterior surface of the nipple 1 for limited arcuate distances, preferably somewhat less than 90°, on diametrically opposite sides of the nipple.

Preferably the nipple 1 is much the same as a conventional pipe nipple externally threaded throughout at least all of its length that is exposed below the wall 3 of the junction box when it is disposed in operative relation therewith. Preferably also the lower inner corner 11 of the nipple is rounded to avoid abrasive or cutting contact with the conductors 12, see Fig. 6, that pass therethrough when my connector is receiving and gripping the armored cable K in its operative and intended relationship. The lower threaded portions of the nipple 1 are also available to receive an insulating and protective bushing 13, shown in dotted lines in Figure 6, which according to known practice overlies the lower end of the nipple and affords a smooth protective and insulating contact with the conductors 12.

40 The clamping members 7 and 8 of my connector are preferably identical, each being stamped and formed of light yielding somewhat resilient sheet stock of conducting material; sheet steel being a preferable material for use with an iron or steel nipple wherewith to be easily secured thereto as by welding. Each of the clamping members is blanked out as shown in Figure 8, the member 8 being therein specifically illustrated

and referred to. In its blanked out form the clamping members each comprise a main body portion, the portion 14 in the member 8 and the portion 14a in the member 7, which with the lower attaching portions 10 and 9 respectively are adapted to be curved in the first instance into substantially true cylindrical form of internal diameter corresponding to the external diameter of the smooth cylindrical exterior of the upper portion of the nipple 1 wherewith the portions 9 and 10, overlying the said upper outer surface of the nipple 1 closely conform to said surface and are readily secured thereto as by spot welding, as shown in other figures of the drawings. Each of the clamping members also comprises clamping tangs; the member 8 having tangs 15 and 16 which, when the members are secured to the nipple, are juxtaposed to the clamping tangs 17 and 18 of the clamping member 7, see also Figures 1 and 7. The several clamping tangs are appropriately apertured to receive clamping screws 19 and 20, Figure 1. The aperture in one of each juxtaposed pair of tangs may be tapped to threadably receive the clamping screws or if desired appropriate nuts for the clamping screws may be provided which may either be free or adhesively secured to the tangs with which they coact. The several clamping tangs are bent outwardly from the body 14 of the stock to stand at substantially right angles thereto along the dotted lines shown in Figure 8; the root of the tang 16 preferably overlying the middle of the corner portion 10 of the member 8 whereby the tang 16 of the member 8 tends to have a relatively fixed portion relative to the nipple during the clamping operation whereas the tang 15 being most remote from the lower corner portion 10 of the member has wide freedom of movement along with the adjacent portions of the body 14 of the member wherewith to accomplish the clamping of the nipple as will more fully appear. Correspondingly the tang 17 of the member 7 is associated with the relatively fixed part of the member while the tang 18 is associated with the relatively movable part thereof.

Each of the clamping members 7 and 8 also comprises a third tang, the tang 21 for the member 8 and the corresponding tang 22 for the member 7, which tangs respectively are bent at right angles to the body portion along the line of the lower free edge thereof to form seats for the lower or innermost end or edge of the armored sheath of the cable K when the same is inserted into the connector and operatively received and gripped therein, see particularly Figures 1, 5 and 6.

The length L of each of the clamping members measured in the direction shown in Figure 8 from the edge 23 of the fixed end of the member 8 to the edge 24 of the free end thereof, i. e. the circumferential length of the main body portion when the members are secured to the nipple, as shown in the other figures, is preferably but slightly less than half the circumference of the exterior of the nipple. When the clamping members are secured to the nipple through their diametrically oppositely disposed portions 9 and 10 respectively, the edge 25 of the fixed end of the member 7 is juxtaposed to and spaced from the edge 24 of the free end of the member 8 and correspondingly the edge 26 of the free end of the member 7 is juxtaposed to and spaced from the edge 23 of the fixed end of the member 8, see Figures 1 and 5. Preferably the spacing between the juxtaposed ends of these members is

a minimum consistent with affording freedom of movement of the free ends of the members radially inwardly and circumferentially with respect to the fixed ends of the members as from the position shown in Figures 1, 4 and 5 to more or less the position shown in Figures 6 and 7 when the clamping members are substantially constricted into gripping engagement with the sheath of the cable K.

The length L' as measured between the root of the tang 15 and the approximate end of the anchor portion as at the dotted line 27, as shown in Figure 8, and correspondingly between similar points in the member 7 is a measure in relation to the length L of the contractability of the clamping members, regard being had for the circumferential space provided between the juxtaposed ends thereof as will more clearly appear from comparison of Figures 1 and 7. The radial contraction of the clamping members of my connector is greatest near but not necessarily immediately adjacent the extreme free ends of the members 7 and 8 but rather in the zone of the seats 21 and 22 as the latter are preferably spaced a little from the extreme free ends 24 and 26 respectively, see Figs. 7 and 8; the free end and swinging part of each clamping member moving both radially and circumferentially inwardly with respect to the fixed end of the opposite clamping member as the juxtaposed tangs are drawn together; the fixed ends of the clamping members adjacent the edges 23 and 25 respectively and above the lower corner portions 10 and 9 respectively serving as the anchors toward and in respect to which the juxtaposed free ends respectively are drawn. Generally speaking each of the body portions of each of the clamping members comprises an anchor portion and an integrally formed free flexible, strap-hinge-like, portion, such that as in the member 8, Fig. 8, that part of the body portion 14 above the portion 10 and rightwardly of the dotted line 27, see also Figure 2, by virtue of its arcuate form and secure attachment to the nipple gives it stiffness and rigidity appropriate for its anchoring function while that part of the body leftwardly of the line 27 is free to swing, flex and bend as the juxtaposed clamping tangs are moved relative to each other. The stiffness of the anchoring portions 25 for a given gauge of stock of the members 7 and 8 is a function of the arcuate length thereof, i. e. of the arcuate length of the portions 9 and 10. It is within the purview of my invention to modify the stiffness of the anchoring portions within desirable limits by modifying the arcuate lengths of the portions 9 and 10; the latter being quite stiff when extending for 90° and correspondingly less stiff when reduced to shorter arcuate lengths. When reduced to about 30° of arc for example the stiffness may well be so reduced as to invite longitudinal bending of the anchor portions, inviting radial inward movement of the upper portion thereof especially when the members are much constricted and facilitating constriction especially of the upper portions of the members in the zone of the clamping tangs wherewith to increase the snugness and unit pressure of the grip at and near the upper edge of the clamping members in relation to the whole gripping force in instances where that mode of operation is found desirable or sought to be achieved.

In the operation of my connector, the same having first been secured in the wall 3 of the outlet box substantially as shown in Figures 1 to 5 inclusive with the clamping members in their

free, normal initial positions, the connector is ready to receive the end of any cable whose external diameter does not exceed the external diameter of the nipple, and with like facility is ready to receive a wide range of cables of lesser diameter down to that to which the connector is ultimately constrictable within the limits hereinabove discussed. The illustrated cable K, having a materially smaller external diameter than the nipple, as shown in Figures 6 and 7, with its armor properly cut off short of the ends of its conductors according to familiar practice, is inserted into the connector with the conductors extending therethrough, the end of the armored sheath entering the connector until the end of the sheath contacts and seats upon the seating portions 21 and 22 of the clamping members; it being advisable to anticipatorily constrict the connecting members to approximately the size of the cable to insure that the seats 21 and 22 both underlie and engage the severed end of the sheath preliminary to making a final clamping grip upon the cable. Thereafter with the parts disposed approximately as shown in Figures 6 and 7 the juxtaposed pairs of tangs of the clamping member are forcibly drawn toward each other preferably with and to substantially like spacings therebetween by the clamping screws 19 and 20; the free end portions of the clamping members first making forcible contact with diametrically opposite sides of the sheath of the cable. Then as the clamping pressure is increased additional increments of the body portions 14 and 14a of the clamping members adjacent the free ends thereof also embrace and make snug and extended contact with the external surface of the sheath depending somewhat upon the flexibility of the body portions of the clamping members, the stiffness of the anchor portions and also upon the amount of constriction thereof required to make the initial contacts. The more nearly the external diameter of the cable to be gripped approaches the external diameter of the nipple the less will be the constriction required to make initial contact and the greater will be the area of contact between the body portions of the clamping member and the surface of the cable upon the next increment of clamping movement. That is to say, my connector inherently tends to grip the larger of the cables that it is capable of receiving a little more snugly and abundantly than it does the smallest sizes which it can receive wherefor it automatically accommodates itself to the burdens and duties it is required to carry and perform.

Throughout the clamping operation the cable is fixed longitudinally of the connector by the radial grip of the members 7 and 8 thereupon and, by virtue of the seat portions 21 and 22 underlying and engaging the extreme end of the armored sheath, the sheath is prevented from deleteriously entering beyond the desired point in the connector and/or in relation to the outlet or junction box. Correspondingly as the clamping members are drawn toward each other in their cable gripping relation and so long as reasonable regard is had for maintaining similar spacing between the juxtaposed clamping tangs the cable as a whole, its sheath and the "tails" of the conductors which extend through the connector and the nipple portion thereof are accurately centered with respect to the longitudinal axis of the connector and from the interior walls and surfaces thereof. Turning back the clamping screws 19 and 20 quickly releases the grip of the clamping members on the cable and permits the

quick release thereof when the same is desired. The integral and/or welded connection between the clamping members and the nipple as well as the tight direct engagement between the lowermost edges 5 and 6 of the clamping members directly with the wall of the outlet or junction box affords a direct positive ground contact and connection between the sheath of the cable and the wall 3 of the box when the cable is gripped in my connector.

The provision of the seats 21 and 22 at and movable with the free portions of the clamping members that have maximum radial motion has the advantage, among other things, of insuring substantially as full and symmetrical a "bottom" for the end of the smaller diameter sheaths to bear and stop upon as a maximum size sheath would have in the absence of the seats 21 and 22 directly upon the upper end surface of the nipple. Thus the seats 21 and 22 contribute in this respect to the adaptability of my connector especially in that part of the range of cable sizes near and less than the internal diameter of the nipple. On the other hand my connector has wide advantage and utility in forms without the seats 21 and 22 especially for the range of sizes of cables, the external diameter of the sheaths of which exceed the inside diameter of the nipple. In such connectors the ends of the sheath are "bottomed" on the top end of the nipple and the clamping operations and results are well and fully performed and accomplished.

The simplicity of construction and design of my connector lends itself to economy of manufacture. Apart from the clamping screws and the three nuts the connector comprises merely a pipe nipple with the pair of identical stamped clamping members welded thereto. Thus I have to make essentially but two different parts, each of which are economically produced. Assembling of the parts involves merely the use of a simple fixture and appropriate welding apparatus. The same simplicity of design that contributes to the ease of manufacture enhances the utility and ruggedness of the finished connector and insures its long life under arduous and varying conditions of service.

Mention has been made of lugs 5a and 6a which I provide as a modified form of my invention to afford a wider bearing area between the connector and the top face of the plate 3 to accommodate the use of my connector with a wider range of tolerance for the diameter of the aperture 2. Preferably the lugs are formed from tangs extending, as the tang 8a in the member 8, Figure 55, beyond the edge 6 and bent at right angles to have their lower surfaces substantially flush with the edges 5 and 6. When it is sought to use my connector with plates having apertures approximately as large or larger than the outside diameter of the portions 9 and 10 then the lugs 5a and 6a, extending to a greater diameter will be available to bear on the plate, juxtaposed to the nut 4, to facilitate clamping the connector to the plate. When the aperture more nearly fits the nipple, as shown in the drawings, the lugs will not interfere with the desirably high unit pressure and electrical contact between the edges 5 and 6 and the plate 3. When the lugs alone make contact with the plate similar advantages are preserved.

While I have illustrated and described a preferred and modified embodiment of my invention, changes, modifications and improvements will occur to those skilled in the art without departing from the substance and spirit thereof and I do

not care to be limited in the scope of my patent to the preferred form herein specifically disclosed nor in any manner other than by the claims appended hereto.

I claim:

1. A cable connector characterized by generally cylindrical oppositely and symmetrically disposed cable clamping members, each having an anchored portion and a circumferentially adjacent free radially swingable portion, the said free portions and anchored portions of the members alternating circumferentially of the connector and the free portion of one member being juxtaposed to the anchored portion of another member, and means for moving the said free portions relative to said anchored portions.

2. The connector of claim 1 with a nipple member rigidly attached to said anchored portions at spaced points at one end thereof, edges of said free portions lying proximate to and spaced from said end with freedom to move transversely thereof.

3. The connector of claim 2 wherein the wall of said nipple is thicker than the thickness of said clamping members and the end of said nipple is flat and normal to the axis thereof, said anchored portions having extensions of limited arcuate length welded to the exterior of the end of said nipple, said clamping members having an initial disposition coaxial of said nipple substantially in the continuation of the external cylindrical surface thereof, the end of said nipple being engageable with the end of the cable sheath to be gripped in said connector.

4. The connector of claim 3 in which said members have clamping tangs at the circumferential ends thereof and said extensions are approximately 90° in arcuate extent and said anchored portions are substantially unyielding radially adjacent said tangs.

5. The connector of claim 1 with a rigid nipple, said anchored portions having extensions of limited arcuate length welded to the end of said nipple, said means comprising clamping tangs associated with the circumferential ends of said members and longitudinally remote from said nipple.

6. The connector of claim 5 in which the arcuate extent of said extensions and anchored portions is small in relation to the longitudinal extent of said anchored portions wherewith to be longitudinally flexible under the influence of said means.

7. The connector of claim 1 with a rigid nipple disposed coaxially of said members, means for

attaching the anchored portions of said members to an end of said nipple and means associated with the free portions of said members upon which the end of a cable sheath may bear.

5. 8. The connector of claim 7 in which said last named means comprises inwardly extending seating tangs carried by said free portions remote from the anchored portions of the same members and adjacent to and movable with respect to the end of the nipple.

9. A cable connector comprising a rigid cylindrical nipple and a pair of cable clamping members secured thereto and extending coaxially thereof, said clamping members being formed of light flexible stock and, in idle open position, defining substantially a right cylindrical extension of the outer cylindrical surface of said nipple, each clamping member being secured at a lower corner thereof to diametrically opposite points 15 on the end of said nipple, each clamping member having approximately 180° of circumferential length in said connector and having an arcuate portion remote from said corner free for movement relative to said corner of each member and 20 lying therebetween, and means for moving the said free portions relative to said corners.

10. The connector of claim 9 in which said corners overlie and conform to the adjacent cylindrical surfaces of said nipple and are welded thereto over a substantial arcuate length thereof and the longitudinally adjacent portions of said member are constrained to substantial rigidity thereby.

11. The connector of claim 10 in which each 35 of said members has a clamping tang extending outwardly near each of its upper corners, one of said tangs of each member being rooted in the substantially rigid portion thereof and juxtaposed to the other tang of the other member.

12. The connector of claim 9 in which said members comprise seats movable with said free portions and engageable with the end of the cable sheath and containing the same against longitudinal inward movement.
